(57) **CLAIM**

I claim the ornamental design for a electronic charger, as shown and described.

DESCRIPTION

FIG. 1 shows the perspective view of a electronic charger showing my new design,

FIG. 2 shows the top plan view thereof,

FIG. 3 shows the left side view thereof, with right side view being the mirror image thereof,

FIG. 4 shows the bottom view thereof,

FIG. 5 shows the rear view thereof; and,

FIG. 6 shows the front view thereof.

1 Claim, 3 Drawing Sheets

FIG. 1

FIG. 2

FIG. 3

FIG. 4

FIG. 5

FIG. 6
